UNITED STATES PATENT OFFICE.

FREDERICK W. HEDGELAND, OF CHICAGO, ILLINOIS.

MACHINE FOR STRINGING PIANOS.

SPECIFICATION forming part of Letters Patent No. 520,595, dated May 29, 1894.

Application filed March 14, 1894. Serial No. 503,577. (No model.)

To all whom it may concern:

Be it known that I, FREDERICK W. HEDGELAND, a citizen of the United States, residing at Chicago, in the county of Cook and State 5 of Illinois, have invented certain new and useful Improvements in Machines for Stringing Pianos, of which the following is a full, clear, and exact description, that will enable others to make and use the same, reference being had 10 to the accompanying drawings, forming a part of this specification.

This invention relates to a machine or device for attaching the strings in the manufacture of pianos, and has for its object to provide 15 a convenient device of this character whereby the operation of stringing a piano or similar musical instrument is greatly facilitated.

In the drawings: Figure 1 is a part elevation 20 and part section, showing the device in position for use; Fig. 2, a broken-away sectional elevation of a part of the device; and Fig. 3, a broken-away plan, showing the position of the device with reference to the tuning-pins and pin-block.

A may represent a pair of horses supporting the respective ends of the piano frame, B the piano back, B' the sounding-board, B² the string or strings, and B³ the tuning pin-block. A rail or bar, C, is rigidly mounted longitudinally on one of the supporting horses or trestles. A sliding-block C' is seated on and engages loosely with the flanged head of the bar C and is adapted to have a longitudinal adjustment thereon in bringing said block into position with reference to the location of the tuning-pins. A post a is swiveled in sliding-block C' so as to be capable of a turning or rotary movement. One end of a two part 40 jointed lever-arm D is pivoted to the post a; the opposite or inner end being pivoted to a lug a' formed on a sleeve D'. The arm D is provided near its longitudinal center with a pivot or hinge-joint a² to permit of a horizontal adjustment. The sleeve D', pivotally connected to the inner end of the lever-arm, loosely incloses a stock E, the respective ends of which project beyond the end of the sleeve, as shown in Fig. 2. The stock is provided 45 with a stop-shoulder a³ which fixes its downward endwise movement with relation to the inclosing sleeve. The upper end of the stock

is provided with a handle a⁴ for the purpose of rotating the same in turning the tuning-pins when attaching the strings. The lower 55 end of the stock has a key-socket or recess a⁵ formed therein which is adapted to fit over and engage loosely with the flattened or square head-end of the tuning-pin or pins b. A driving-rod F is inserted longitudinally 60 through the stock, stopping just short of the lower end thereof. The lower end of this rod is intended to have contact with the head-end of the tuning-pins, so that a tap on the upper end will drive in the pin. A shoulder b' 65 limits the downward movement of the driving-rod so that the pins cannot be driven into the pin-block beyond a certain point. A rod or string-lifter d is inserted through a chamber d', formed on the sleeve D', and has its lower 70 end turned at right-angles to bear against the tuning-pins and hold the strings at the required height and force the coils closely together as they are formed on the pin. A spring d², located in chamber d' and coiled 75 on rod d is intended to exert an upward or lifting pressure on the string or coil through the medium of the rod d. By means of a handle d³, mounted on the upper end of rod d, the lifter may be turned to disengage the 80 same from the springs. A cam-lever d' is pivotally connected to the sleeve D'; the cam-end being adapted to have contact with the upper end of the string-lifting rod and force the same downwardly against the tension of 85 spring d², so that the lifter-rod may be conveniently disengaged. A gage-screw g is inserted down through the lever-arm and has a bearing on slide-block C'. The function of this screw is to raise or lower the inner end 90 of the lever-arm and the sleeve and stock carried thereon so that these parts may be adjusted to the required position with reference to the setting of the tuning-pins. By means of the sliding pivotal support and the jointed 95 lever-arm, the sleeve and stock of the device may be turned to any angle or position to engage with each of the tuning-pins in order, as the operation of attaching the strings progresses.

In practical working, the end of the string is secured to the tuning-pin in the usual manner, which is, loosely inserted in the pin-block. The lower end of the stock is then

made to engage with the head of the pin and rotated, which imparts a corresponding movement to the pin, until the required number of coils have been formed, a blow on the driving-rod sets the pin, the string-lifter is then disengaged by the means described and the device swung to engage with another pin, and so on until the operation is completed.

I do not limit or confine myself to the precise details and arrangement shown, but may make such changes as practical working may require without departing from the spirit of my invention.

Having thus described my invention, what I claim as new, and desire to secure by Letters Patent, is--

1. In a device of the kind described, the combination with a jointed lever-arm, pivotally supported at its outer end, a sleeve, having a pivotal connection with the opposite or inner end of said arm, a stock, loosely inclosed by said sleeve and provided in its lower end with a socket or recess to engage with the head-end of a tuning-pin in the operation of attaching the strings, substantially as set forth.

2. In a device of the kind described, the combination with a jointed lever-arm, having a pivotal connection and swiveling support at its upper end, a sleeve, pivoted to the inner or opposite end of said arm, a stock, inclosed and supported by said sleeve and adapted to engage with the head-end of the tuning-pins, and a handle, for rotating said stock, substantially as set forth.

3. In a device of the kind described, the combination with the stock, adapted to engage with and rotate the tuning-pins, of a driving-rod, inserted longitudinally therethrough and having contact with the tuning-pin, whereby the pin or pins may be forced in and seated in the operation of stringing a piano, substantially as set forth.

4. In a device of the kind described, the

combination with a jointed lever-arm, pivotally connected at its outer end, a sleeve, pivotally connected to the inner end of said arm, a stock, loosely inclosed by said sleeve, a rotating handle, attached to the stock, and a driving-rod, inserted in said stock, substantially as set forth.

5. In a device of the kind described, the combination with a suitable stationary support, of a sliding-block, adjustably mounted on said support, a post, swiveled in said block, a jointed lever-arm, pivoted at one end to said post, a sleeve, pivoted to and supported on the opposite end of said arm, a stock, supported in said sleeve, a rotating handle attached to said stock, and a driving-rod, inserted longitudinally in said stock, substantially as set forth.

6. In a device of the kind described, the combination with a sleeve, provided with chamber, of a string-lifting rod, extending through said chamber, a spring, located in said chamber and coiled on said rod, and a cam-lever, pivoted to said sleeve and adapted to shift said rod against the tension of the spring in disengaging the lifter, substantially as set forth.

7. In a device of the kind described, the combination with an adjustable support, of a jointed lever-arm, pivoted at one end thereto, a sleeve, pivoted to the opposite end of said arm, a stock, loosely supported in the sleeve, a rotating handle, a driving-rod, inserted in said stock, a string-lifting rod, attached to said sleeve, a spring, coiled on said rod, and a cam-lever, pivoted to said rod and having contact with said lifting-rod, substantially as set forth.

FREDERICK W. HEDGELAND.
